JACK

Filed June 18, 1926

UNITED STATES PATENT OFFICE

JOHN M. CANTWELL, OF TARRYTOWN, NEW YORK

JACK

Application filed June 18, 1926. Serial No. 116,780.

This invention relates to screw lifting jacks particularly adapted for motor vehicles, the object of the invention being to provide an improved jack of this class, simple in construction, strong, durable, powerful in use, and easily operated.

Another object of the invention is the provision of an improved combined lifting jack and rim tool which may be used, not only for the removal of the shoes from the rims, but for materially increasing the height of the jack when necessary.

The particular object of the present invention is the provision of an improved screw jack which can be readily and inexpensively manufactured and so constructed that it can be readily used for a very low lift or easily extended for a high or extra high lift, as may be necessary.

In the drawings accompanying and forming a part of this specification, Figure 1 is a vertical sectional view of this improved screw jack, illustrating the tire irons in position for use as an extension of the jack, one of the rim members being shown connected with the base plate of the jack; Fig. 2 is a partly sectional view illustrating the screws of the jack extended and also illustrating one of the rim members in place on the base; Fig. 3 is a cross-sectional view, taken in line 3—3 of Fig. 1.

Similar characters of reference indicate corresponding parts in the several figures of the drawings.

Before explaining in detail the present improvement and mode of operation thereof, I desire to have it understood that the invention is not limited to the details of construction and arrangement of parts which are illustrated in the accompanying drawings, since the invention is capable of other embodiments, and that the phraseology which I employ is for the purpose of description and not of limitation.

This improved jack in its preferred form comprises a suitable casing 2 flanged at its lower end as at 3, to which is attached by screws a base plate 4. This casing comprises a cylindrical portion 5 having an enlarged chamber 6 and having at its upper end an

inwardly extending flange 7. Located in this casing is a rotatable tubular sleeve 8, the upper end of which is overlapped by the flange 7 of the casing while the lower end rests upon the base plate 4, thus preventing 55 lengthwise movement of the sleeve 8. The sleeve 8 is provided with a large bevel gear 9 shown formed as a part thereof, and in mesh with this bevel gear is a small bevel gear 10 carried by a suitable bracket or support 11 attached to a removable plate 10'. This removable plate is by suitable screws attached to an inclined portion of the casing and affords access to the casing and the proper positioning of the bevel gear 10. The 60 bevel gear 10 is provided with a square ended spindle 12 for the reception of a crank or handle by means of which it may be rotated thereby to rotate the bevel gear 9 and the tubular sleeve 8.

Within the rotary tubular sleeve 8 is a pair of telescopic screws 13 and 14, both of the same length, the screw 13 being in the form of a tubular member having exterior threads 15 along its length meshing with a threaded portion or collar 16 carried at the upper end of the tubular sleeve 8. This tubular screw 13 is also provided at its upper end with an interiorly threaded portion or collar 17 meshing with threads 18 located along the length 75 of the screw 14, which is shown as a solid bar. The tubular screw 13 is provided exteriorly with a longitudinal slot or key way 19 for the reception of a spring pressed tooth or plunger key 20 carried at the upper end of 80 the casing, and which may be inserted or removed through an opening closed by a suitable threaded plug 21. These screws 13 and 14 are completely housed within the casing 2, which can be comparatively low, thus enabling the jack to have a very low lift and yet be extended to give a very high lift. The tubular screw member 13 has its threads smoothed or slabbed off at its upper end as 85 at 22 and also smoothed or slabbed off at its lower end as at 23 and with which the longitudinal slot 19 communicates. The screw member 14 is provided with a suitable pin for limiting the upward movement thereof, this pin coming into engagement with the thread- 90 95 100

ed portion 17 of the tubular screw member and the tubular screw member is likewise provided with a suitable pin at its lower end which, when it comes into engagement with the threads of the sleeve 8, will limit its upward movement. The top of the screw member 14 is squared for the reception of a supporting head 24, which is pinned thereto and this head is slotted at its ends as at 25, the slots terminating in circular recesses 25' for the reception of the stirrup bars 25" of a pair of tire irons 26. These tire irons can, by means of the slotted circular recesses 25', be swung up or down and can also be removed due to the fact that the stirrup bars are flattened. In other words, these flattened portions correspond in thickness substantially to the slotted portions of the recesses while at right angles to the flattened portions they correspond substantially to the circular portions thereof. One of the irons is provided with a step 27 of tapered form and this step projects into an opening 29 in the other iron when the irons are swung into a vertical position, the step serving as a means of wedging the two together to hold the irons in such position. The step is provided with an opening 28 for the reception of a cotter pin. This holding or locking step 27 may also be used as a step of the jack when desired, both irons in this case being of course swung downward, thus providing a step below the top of the screws in any position of those screws, so that when the screws are telescoped the step 35 will be very close to the ground or road bed thus providing a means for engaging the axle or under frame of a car in the event that the wheels are sunk in the mud or sand or in other emergencies where there is but small 40 space between the road bed and the frame or axle of the car. The tops of the irons have suitable extensions 32 adapting them to be used as rim tools while the opposite parts 32' can be used as steps of the jack when the irons 45 are in the position shown in Fig. 1. When the irons are to be used as a rim tool, a bifurcated plate 30 may be slipped over the base plate in the manner shown in Figs. 1 and 2, this plate being provided with a tongue or projection 31 somewhat similar to those, as 50 32, formed at the tops of the tire irons.

In the operation of this improved jack, the rotation of the small bevel gear 10 rotates the bevel gear 9 and the sleeve 8 which is of course held against longitudinal movement by the base plate and flange 7. The rotation of this sleeve around the tubular screw 13 forces it upward, the rotation of the screw 13 being prevented by the tooth 20 55 passing along the longitudinal slot 19 of the screw 13. This upward movement of the tubular outer screw 13 carries with it the inner screw 14 without however rotating or extending it. When, however, the screw 13 60 has reached its extended position the tooth

21 passes out of the slot 19 and registers with the lower slabbed portion 23 of the screw 13 and in consequence the screw 13 will then be rotated by the tubular sleeve 8, as the tooth 21 will then simply roll over 70 the lower threads of the screw 13. This rotation of the screw 13 then rotates and projects the inner screw 14 until the same has been fully extended. If the height of the jack is not then sufficient, the tire irons 75 may be thrown upward and used, with the parts 32' in position to engage the axle or under frame of the car, as shown in Fig. 1 to increase further the height of the jack. A reverse operation first lowers the screw 80 13 as soon as the rotation thereof brings the slot 19 opposite the tooth 20, until it has been fully lowered. When the slabbed off portion 22 comes opposite the tooth 20, the tubular screw 13 will then be rotated again 85 by the sleeve 8, therupon to rotate the inner screw 14 and lower it in a manner which will readily be understood. In spreading the shoe rim, it is necessary merely to use the upper tire iron and not the lower ones, 90 since the base of the jack may be used against the rim. In contracting the rim, however, the lower tire iron 30 would be used.

From the foregoing, it will be observed 95 that if each screw above its overlapping part is eight inches in height, a lifting jack is provided having a total lift of 16 inches without the use of the tire irons, while with the use of the tire irons the height of the jack is materially increased, according to 100 the length of the tire irons, thus providing a jack which is useful for many purposes and particularly useful for motor vehicles where the underframe or axles are low hung or close to the ground. 105

Furthermore, it will be observed that both screws are of the same length and yet are no greater in length than the casing.

It will be further observed that the bevel gear 9 is formed as a part of the sleeve 8 so that the sleeve and the bevel gear can be one casting with the sleeve at its center resting directly on the base plate 4 without the necessity of providing any ball races, since the sleeve 8 has a tapered lower end provided with a hardened steel rivet or knob 10" so that the frictional resistance is very slight. Should there be any tendency of lateral movement at the lower end of the sleeve 8, the base plate 4 can be provided 110 with a depression for the knob or rivet 10" to fit into, similar to that shown in my co-pending application, Serial No. 171,498, filed February 28, 1927, although it is believed 115 that the frictional engagement of the rivet 10" with the base 4 when load is upon the jack, together with the fact that there is considerable bearing surface between the upper end of the sleeve 8 and the casing 5 is sufficient to prevent any such lateral move- 120 125 130 135

ment. Further, as the threads 16 and 17 are formed as parts of the screws 13 and 14 respectively, this eliminates the necessity of providing separate pinned collars likely to be displaced, and by slabbing off the threads of the screw 13 as at 22 and 23 the necessity of specially forming a separate annular groove is avoided, while the provision of a spring pressed tooth which can be easily removed and replaced when worn is permitted.

These improved features together with others and the improved form of tire irons very much simplify the construction, decreasing the cost of manufacture and rendering the jack more easily operated, so that the same forms an improved jack over that shown and described in my Patent No. 1,540,511, dated June 2, 1925.

It is to be understood that by describing in detail herein any particular form, structure or arrangement, it is not intended to limit the invention beyond the terms of the several claims or the requirements of the prior art.

Having thus explained the nature of my said invention and described a way of constructing and using the same, although without attempting to set forth all of the forms in which it may be made, or all of the modes of its use, I claim:

1. In a screw lifting jack, the combination of a supporting casing, a pair of telescopic lifting screws within said casing, the outer telescopic screw having slabbed portions at its top and bottom communicating with a longitudinal key way, and a spring pressed plunger carried at the upper end of the casing and cooperating at different times with said slabbed portions and key way, and means for lifting one of said screws without rotating it and for then rotating it thereby to lift the other screw and including a rotatable tubular sleeve also housed entirely within and extending substantially from end to end of said casing, and gear mechanism connected adjacent to the lower end of said sleeve for rotating said sleeve.

2. In a screw lifting jack, the combination of a supporting casing, a pair of telescopic lifting screws, one comprising a tubular exteriorly threaded member having integral interior threads at its upper end, a spring pressed plunger for preventing the rotation of said threaded tubular member at one time, said member having slabbed portions at its top and bottom and a longitudinal key way communicating therewith for cooperation with said spring pressed plunger, means for lifting one of said screws without rotating it and for then rotating it thereby to lift the other screw and including a rotatable tubular sleeve housed entirely within and extending substantially from end to end of said casing and having integral interiorly located threads at its upper end and an integral bevel

gear, and a gear cooperating with said bevel gear for rotating said tubular sleeve.

3. In a lifting jack, the combination of a pair of telescopic inner and outer screws operatively connected, a threaded sleeve embracing said outer screw for operating the same, a supporting casing housing said sleeve entirely within the same, said sleeve extending substantially from end to end of the casing, and a spring pressed plunger carried at the upper end of said casing, said outer screw having a vertical keyway for receiving said plunger and terminating in a pair of slabbed portions at its upper and lower ends to permit the plunger to pass around the threads adjacent to said slabbed portions.

4. In a lifting jack, the combination of a pair of telescopic inner and outer screws operatively connected, a threaded sleeve embracing said outer screw for operating the same, a supporting casing housing said sleeve entirely within the same, said sleeve extending substantially from end to end of the casing, and a spring pressed plunger carried at the upper end of said casing, said outer screw having a vertical keyway for receiving said plunger and terminating in a pair of slabbed portions at its upper and lower ends to permit the plunger to pass around the threads adjacent to said slabbed portions, said threaded sleeve also having a bevel gear and said gear and sleeve being formed as a single casting.

5. In a lifting jack, the combination of a supporting casing, a pair of telescopic lifting screws, means for lifting one of said screws without rotating it and for then rotating it to lift the other screw and including a vertically extending rotatable sleeve embracing one of said screws and housing entirely within and extending substantially from end to end of the casing, gear means connected to said sleeve for rotating the same, a spring pressed plunger located at the upper end of the casing, and means cooperating therewith and comprising a vertical slot carried by the outer telescopic screw and a pair of slabbed portions at the ends of said slot for permitting in sequence sliding and rotating movements of the outer screw.

6. In a screw lifting jack, the combination of a casing, a rotatable sleeve located entirely within and extending substantially from end to end of said casing and having a bevel gear and a threaded portion at its upper end a tubular exteriorly threaded screw cooperating with the threaded portion of said sleeve and having an interiorly threaded portion at its upper end, a telescopic screw within said threaded screw, said outer screw having a key way and a pair of slabbed portions at the opposite ends of said key way, a spring pressed plunger carried by said casing and cooperating in sequence with a slabbed portion and the key way, and means for rotating said outer sleeve whereby on the rotation

of said outer sleeve the outer screw will be extended without rotation thereof and will then be rotated to rotate the inner screw.

7. In a lifting jack, the combination of supporting means, a lifting member, means for operating the same, said member having a head, a pair of tire irons swingingly carried thereby, one of said irons having an opening and the other a jack-lifting step projecting thereinto.

10 8. In a lifting jack, the combination of supporting means, a lifting member, means for operating the same, said member having a head, a pair of tire irons swingingly carried thereby, one of said irons having an opening and the other a jack-lifting step projecting thereinto, said jack-lifting step having a wedge formation.

9. In a lifting jack, the combination of a 20 casing, a pair of telescopic inner and outer screws located therein and operatively connected, means for operating the same successively, and a spring pressed plunger carried at the upper end of said casing, said outer screw having a vertical key way for receiving said plunger and terminating in a pair of laterally slabbed portions at its upper and lower ends to permit the plunger to pass around the threads adjacent to said slabbed portions.

10. In a screw lifting jack, the combination of a supporting casing, a pair of telescopic lifting screws of the same length and both corresponding with the length of the 35 casing and completely housed within said casing, a rotatable sleeve located entirely within and extending substantially from end to end of said casing, means for rotating the sleeve, and means for permitting the rotation of the outer screw at one time and preventing its rotation at another and comprising a key way and slabbed portions carried by the outer screw at the ends of said key way, and a spring pressed plunger carried at the upper end of the casing.

11. In a lifting jack the combination of supporting means, a lifting member, means for operating the same, said member having a head, a pair of tire irons swingingly carried by said head and adapted to be swung up or down, one of said irons having a step projecting therefrom in position for use below the top of the jack in any position of the lifting member and said irons having means for connecting them when swung into position to operate as an extension of the jack.

12. In a lifting jack the combination of supporting means, a pair of telescopic screws carried thereby, means for operating the 50 same, a head carried by one of said screws, a pair of tire irons swingingly carried by said head and adapted to be swung up or down, one of said tire irons having a step projecting therefrom in position for use below the top 65 of the jack in any position of the screws.

13. In a lifting jack the combination of supporting means, a pair of telescopic screws carried thereby, means for operating the same, a head carried by one of said screws, a pair of tire irons swingingly carried by said head and adapted to be swung up or down, one of said tire irons having a step projecting therefrom in position for use below the top of the jack in any position of the screws and the other iron having an opening for the reception of said step when the irons are swung upward.

70 14. A tire iron for use with a jack having a hook-shaped rim engaging end, an integral stirrup formed opposite end, and a jack step therebetween.

15. A pair of tire irons for use with a jack each having a hook-shaped rim engaging end and a stirrup formed opposite end, one of said irons having a jack step and the other an opening for the reception of such step.

85 16. A jack comprising a base, lifting means carried thereby, means for operating it, and tire removing means comprising a member adapted to engage the base of the jack and provided with means for engaging the rim of a tire, and swinging means carried by the lifting means and provided with means for also engaging the rim of a tire and with a jack step between the ends thereof, and means carried by said swinging members for connecting them when swung into position to operate as an extension of the jack.

90 Signed at 1822—3—4 Park Row Building, New York city, N. Y., this 7th day of June, 1926.
